(57) **CLAIM**

The ornamental design for a bilateral handheld massager as shown and described.

DESCRIPTION

FIG. 1 is a front perspective view of a bilateral handheld massager, as showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof;

FIG. 9 is a partial enlarged view of the portion of FIG. 1;

FIG. 10 is a partial enlarged view of the portion of FIG. 1;

FIG. 11 is a partial enlarged view of the portion of FIG. 1;

FIG. 12 is a partial enlarged view of the portion of FIG. 1;

FIG. 13 is a partial enlarged view of the portion of FIG. 1;

FIG. 14 is a partial enlarged view of the portion of FIG. 2;

and,

FIG. 15 is a partial enlarged view of the portion of FIG. 2.

The dash-dash broken lines shown in the drawings are for the purpose of illustrating portions of the bilateral handheld massager, which form no part of the claimed design. The dot-dash broken lines shown in FIGS. 1, 2, 9, 10, 11, 12, 13, 14, and 15 represent the boundaries of the enlarged areas and form no part of the claimed design.
